UNITED STATES PATENT OFFICE.

ABRAM D. EMERY, OF TAUNTON, MASSACHUSETTS.

WOVEN SEAMLESS BAG.

SPECIFICATION forming part of Letters Patent No. 415,148, dated November 12, 1889.

Application filed May 31, 1889. Serial No. 312,826. (No specimens.)

To all whom it may concern:

Be it known that I, ABRAM D. EMERY, a citizen of the United States, residing at Taunton, in the county of Bristol and State of Massachusetts, have invented certain new and useful Improvements in Woven Seamless Bags, of which the following is a full description.

My invention relates to woven seamless bags; and it consists, generally speaking, in a seamless bag composed of a set of chain-threads and two distinct weft-threads, which traverse the chain-threads of opposite sides of the bag for two successive picks, and are then transferred at the bottom of the bag to opposite positions in the bag for two successive picks, and so on, the sides of the bag being bound together by passing the two weft-threads through all the chain-threads. The body of the bag, consisting of the two sides, the closed bottom, and the open mouth, is essentially the fabric described and claimed by me in an application filed February 28, 1888, Serial No. 265,581, (Case 2,) and is formed by the method of weaving described and claimed by me in an application filed February 28, 1888, Serial No. 265,639, (Case 1.) In the body of the bag separate weft-threads, starting from opposite selvages located at the mouth of the bag, make passages to the bottom of the bag, where they pass each other and cross one over and one under and then pass onward through a succeeding pick to the opposite selvages from which they started, then return through a succeeding pick from those selvages to the bottom of the bag, where they again pass by each other and cross one over and one under and then return through a succeeding pick to the selvages at the mouth, from which they started, the formation being continued for the desired distance. At given points where the sides of the bag are closed together the chain-threads are interlaced around the weft-threads, binding the two sides together. In this formation of the fabric the mouth of the bag consists of the two selvage edges, formed by the weft-threads passing to and from said edges and around the outer chain-threads at that point. The bottom of the bag is formed by the continuous passage of the weft-threads around the fabric at that point from one side to the other, it being further strengthened and made perfect by the crossing of the weft-threads at that point by their passage into succeeding sheddings. The closed sides of

the bag are formed by the interlacing of the weft-threads and chain-threads. In this formation a given weft-thread is in one half of the fabric for two successive picks, and is then in the opposite half of the fabric for two successive picks, the same being true of the other weft-thread in the reverse sense. The sides of the bag are united by passing the chain-threads of one side of the fabric to the other side and over the weft-threads, forming that side of the bag in regular order, so that at all times there is one chain-thread on each side of each weft-thread, or one on each outside and two between or inside the two weft-threads. The chain-threads all assume the several positions in regular order.

In the accompanying drawings, forming part of this specification, Figure 1 is a plan view of the bag with the threads separated and enlarged to show the formation. Fig. 2 is a side view showing the opening or mouth. Fig. 3 is a cross-section parallel with the mouth of the bag across the weft-threads through the lines C D, Fig. 1. Fig. 4 is a side view of the bottom of the bag, showing the direction of the weft-threads as they pass from one side to the other. Fig. 5 is a cross-section taken lengthwise or parallel with the united sides of the bag through the chain-threads at the points A B.

One weft-thread is designated by the numeral 5, and is shown as shaded, the other weft-thread being designated by the numeral 6, and shown as plain. One half of the chain-threads, forming one side of the bag, are designated by the numerals 1 and 3, while the other half, forming the opposite side of the bag, are designated by the numerals 2 and 4.

Referring to Figs. 1 and 2, it will be seen that a weft-thread, as already explained, is on one side of the opening forming the mouth of the bag for two successive picks, and that the two opposite parts of the picks in the fabric or bag are formed by the other weft-thread, and that at the next two picks the position of the weft-threads in this regard is reversed. This reversing of the position of the weft-threads is due, of course, to the fact that on the closed side B the weft-threads pass by each other and are transferred to opposite positions in the fabric, thereby closing the bottom of the bag, as more particularly shown in Fig. 4, the shaded thread uniformly crossing over the plain thread in the formation illus-

trated. At the mouth of the bag the weft-threads do not pass by each other, but return to the same side just traversed and around the outer chain-thread of that side, forming a selvage edge. The fabric thus formed and the method of weaving employed are fully explained in the applications heretofore referred to, and require no further description.

It will be observed that the mouth of the bag has selvage edges, the two opposite parts of the mouth being formed simultaneously by the two weft-threads, one part by each. The wefts simultaneously turn the edges at diametrically-opposite points, each weft appearing at one selvage or the other at each second pick, and they alternately turn one edge and then the other, and so on, the two wefts being on opposite sides of the mouth at all times.

The formation of the fabric constituting the closed sides of the bag consists, generally, in causing the chain-threads to pass from one side of the bag or fabric to the other in a distinct manner, as illustrated in Fig. 3, which is a cross-section of the weft-threads. It will be observed that at the right-hand side of the figure the chain-thread 4 is outside of the weft-thread 6 and chain-thread 3 is outside of weft-thread 5, while chain-thread 2 is inside weft-thread 6 and chain-thread 1 is inside weft-thread 5. This is the position the threads would assume in the two halves as formed separately. At the next pick, however, chain-threads 1 and 2 will be seen on the outside, the same as in the previous pick; but chain-threads 3 and 4 are shown as passing to opposite sides and are crossed in the center. At the next pick the threads 3 and 4 are again on the outside, but on opposite sides of the bag or fabric. Thus thread 4 has passed from side E to the outside of the side G and thread 3 has passed from the side G to the side E. At the next pick these threads are in the center, and at the following pick are on the outside of the sides from which they started—that is, thread 4 is on the side E, while thread 3 is on the side G. Thus it will be observed that there is always one thread on each outside and two threads between at each pick during the process of binding the two sides together into a single fabric, and that at the end of four picks a chain-thread has passed through the fabric between the weft-threads and assumed its original position. This order is taken in succession by each of the four chain-threads, it being understood that the several chain-threads in the fabric are in sequences of four across the face of the same, and that they all assume these positions in succession, as will be seen upon examining the plan view of Fig. 1, and is fully explained in the application before referred to.

Referring to the crossing of the weft-threads at the closed edge constituting the bottom of the bag, it will be seen in Fig. 5

that the crossing takes place between the chain-thread 1 of one half and chain-thread 2 of the other half of the fabric or bag, the weft-thread 5 passing over chain-thread 2 and under chain-thread 1, and the weft-thread 6 passing over chain-thread 1 and under chain-thread 2. At the next pick weft-thread 5 will pass under chain-thread 2 and over chain-thread 1, and weft-thread 6 will pass under chain-thread 1 and over chain-thread 2. This manner of crossing the threads 5 and 6 is preferably maintained throughout the part that unites the sides together. 80

The bag herein described is to be distinguished from the bag which is the subject of application filed by me May 31, 1889, Serial No. 312,833, (Case 18,) and which is made by the method described and claimed in application filed by me July 22, 1889, Serial No. 318,249, (Case 20.) In that bag, and in the method by which the same is produced, the mouth is formed of the selvage edges at one side of the loom; but the weft-threads are interlaced with all the chain-threads on all three sides that are closed in the process of weaving, whereas in the present case the weft-threads do not pass through all the chain-threads at the bottom of the bag, which is closed simply by the passage of the weft-threads into opposite sides of the bag at that point. The bag of the present case is made by the method which is the subject of application filed by me May 31, 1889, Serial No. 312,827, (Case 12.) 95

The term "pick" as used in this specification signifies a complete layer of weft composed of one weft-thread on one side of the bag and the other weft-thread on the other side of the bag. These two weft-threads are laid at one operation in the weaving by the simultaneous passage of two shuttles through a double shedding, as explained in Case 12, referred to. 110

What I claim is—

1. A seamless bag containing two weft-threads, and in which the bottom and sides are closed in the process of weaving, the mouth having selvage edges, and the two wefts appearing alternately in each side of the bag and turning the edge thereof alternately. 115

2. A seamless bag composed of a set of chain-threads and two weft-threads, each occupying a half of each pick, and which weft-threads are transferred at the bottom of the bag at each second pick into opposite positions in the bag, said weft-threads passing through all the chain-threads to form the closed sides of the bag. 120 125

In testimony whereof I have hereunto set my hand this 29th day of May, A. D. 1889.
